UNITED STATES PATENT OFFICE

JOHAN PEHRSSON, OF SKILLINGARYD, SWEDEN

ADJUSTABLE WRENCH

Application filed December 17, 1929, Serial No. 414,744, and in Sweden January 4, 1929.

My present invention refers to an improvement in adjustable wrenches of the kind wherein a fixed jaw connected to a handle for the purpose of obtaining the desired gripping action coacts with another jaw movably mounted in the handle, or in a wrench head connected therewith, such movable jaw being combined with a toothed member or rack which, for the purpose of adjustment, stands in permanent engagement with a toothed transmission member pivotally mounted in said handle or wrench head.

Adjustable wrenches of the kind referred to above are already known, and the invention has for its primary object to provide improved means for locking the adjustable jaw in its desired positions relatively to the fixed one, whereby the said locking of the adjustable jaw and hence, the fixing of the gripping width of the wrench according to the invention are effected by locking means coacting with the rotatable transmission member, or with some part rigidly connected therewith and acting against a fixed abutment surface on the handle or wrench head, so that the adjustable jaw is locked indirectly by the intermediary of said transmission member.

According to a preferred embodiment of the invention the locking member is constructed in the form of an automatically acting friction locking means, so that the adjustable jaw is automatically locked after adjustment as soon as the adjusting member is released. It is to be understood, however, that the locking means need not by necessity act by means of friction, although locking means of this kind are to be preferred, and it may also act by means of teeth or serrations and consist for instance of a number of locking pawls, as will be more fully explained in the following.

By using a locking means of the kind stated the advantage is gained, however, that the locking of the adjustable jaw may be effected in any position independently of the pitch of the coacting toothed parts serving the purpose of transmitting the movement between the transmission member and

the adjustable jaw; and by permitting the locking means to act on the transmission member instead of acting directly on the adjustable jaw, the parts required for the locking can be positioned backwardly towards the handle end of the wrench, so that they do not cause any unnecessary increase of dimensions at the forward end of the same, i. e. adjacent to the gripping jaws. An increase of dimensions at such latter place is frequently disadvantageous and to be considered as a drawback, especially when the wrench is to be used on screws or nuts in difficultly-accessible positions. Besides, the entire device according to the invention for transmitting the movement between the adjusting member and the adjustable jaw and for locking the latter is constructed in such a manner that it does not substantially increase the dimensions of the handle or wrench head beyond the dimensions required in any case for the sake of strength.

In the following the invention is to be described with reference to the accompanying drawings showing a number of embodiments thereof. In the drawings:

Fig. 1 shows a plan view of the wrench,

Fig. 2 is a similar plan view in which the adjusting member is removed for the purpose of showing the interior construction, and

Fig. 3 is a section on the line 3-3 in Fig. 1.

Fig. 4 is a section through the wrench head at right angles to the axis of rotation of the rotatable parts, showing a modified form of the transmission means for causing the adjusting movement of the movable jaw, and

Fig. 5 in the same manner shows still another embodiment thereof.

Fig. 6 shows a plan view of a modified form of the adjusting member, and

Fig. 7 shows a side elevation of the latter.

Fig. 8 is a plan view of the wrench showing another modified form of the adjusting member, and

Fig. 9 is a section on the line 9-9 in Fig. 8.

Fig. 10 is a plan view showing still an-

other modification of the adjusting member.

Fig. 11 is a view similar to Fig. 2 but showing an embodiment of the invention in which the friction locking means is substituted by locking pawls, and

Fig. 12 is a section on the line 12—12 in Fig. 11.

Referring to Figs. 1-3, 1 is the wrench handle and 2 a head member thereon, such head member being rigidly connected with a fixed jaw 3. An adjustable jaw 4 is slidably mounted in the wrench head 2 and provided with a toothed rack portion 5 in mesh with a toothed wheel 6 rotatably mounted in the wrench head on the bolt 7, the wrench head being provided with a cylindrical bore 8 surrounding the wheel 6, which latter fits rather snugly in the bore, as will be understood from Fig. 2.

At one side, the wrench head 2 is provided with a cylindrical countersunk portion 9 positioned coaxially with the bore 8 and forming a seat for a locking disc 10 suitably affixed to the wheel 6 or constructed in one piece therewith, so that the said wheel and disc will rotate as a common unit. At its free edge the disc 10 is provided with a number of peripheral recesses 11, the bottom faces of which are eccentrically positioned or otherwise tapering in relation to the cylindrical inner face of the countersunk portion 9. According to Figs. 1-3 the number of such recesses is four, but any other number thereof can be used.

In each of the recesses 11 there is provided a ball or roller 12 acted upon by a spring 13 tending to press the same towards the restricted end of the corresponding recess, so as to obtain, in this way, by means of the ball or roller 12, a frictional locking action between the disc 10 and the inner cylindrical face of the countersunk portion 9, such face forming a fixed locking abutment for the disc and, consequently, also for the toothed wheel 6 connected with the latter. Hence, the adjustable jaw 4 will also be locked by the same means. In this connection it is specifically to be understood that the members 12 need not by necessity be given the shape of balls or rollers, although this shape is to be preferred, but they may also take the form of wedge-shaped blocks for the same purpose.

Outside of the disc 10, the interior cavity of the wrench head and the parts of construction at hand therein are covered by means of a washer 14 (removed in Fig. 2), such washer serving as an adjusting member. For this purpose the washer 14 is provided with one or more radial arms 15 (Fig. 1) so as to be turned by hand for manual adjustment of the gripping width, i. e. the distance between the jaws. The washer 14 is provided with a number of inwardly projecting pins 16. One of such pins 16 is lo-

cated in each of the recesses at that side of the movable locking member 12 therein opposite to the side acted upon by the corresponding spring 13, from which it will be understood without further explanation that a turning movement of the washer 14 in a direction to displace the locking members 12 in opposition to the springs, will release the disc 10 and thereby also the wheel 6 and the adjustable jaw 4.

In order to arrest the disc 10 a little during the adjustment, said disc is acted upon by one or more friction brakes or arresters of a resilient kind. An embodiment thereof is shown in Fig. 3, according to which the end of a pin 17 acted upon by a spring 18 is in contact with the inner face of the disc 10 and serves the purpose of arresting the same. The aforesaid arresting members are mounted in a corresponding bore in the wrench head, and a plurality of such means can naturally be at hand if desired.

The end of the wrench head cavity opposite to that closed by the washer 14, is closed by a similar washer 19 (Fig. 3), and said washers may be interconnected by means of the central bolt 7 serving as a shaft for the rotatable parts. The washer 19 need not rotate during the adjustment, as the result will be the same even if it is rotated together with the washer 14. Therefore both of the washers can be rigidly affixed to the bolt 7, or the washer 14 can be rotatably mounted thereon. On the other hand the washer 14 can also be affixed to the bolt, and the latter rotatably mounted in the washer 19.

In order to make it possible to reduce the thickness of the wrench head, the modifications according to Figs. 4 and 5 can be used. In these embodiments the disc 10^a is directly provided with teeth 6^a at a part of its circumference, so that the disc and the toothed segment thus formed are positioned substantially in the same plane. As the toothed segment 6^a occupies a part of the circumference of the disc, the recesses 11 cannot be equally spaced all around the circumference as in Figs. 1-3, but must occupy only the part not occupied by the toothed segment. According to Fig. 4 the disc is provided with a single recess 11 only and forms substantially a double-armed lever, one arm of which is provided with teeth and the other with the locking recess. According to Fig. 5 the recesses are positioned to the full extent of that part of the circumference of the disc not occupied by the toothed segment, and they are three in number. In other respects the modifications according to Figs. 4 and 5 are identical with the embodiment first described, and in each of the recesses there are provided a locking member 12, a spring 13 and a pin 16, which latter is connected with an adjusting mem-

ber similar to that one described above. Arresting means of a kind similar to the means 17, 18 may also be used in connection with the modifications shown in Figs. 4 and 5, especially in connection with the latter; and for the purpose of using similar arresting means in connection with the modification according to Fig. 4, the part of the disc nearest to the recess 11 may be provided 10 with a peripheral extension adapted for coaction with such arresting means (not shown in the drawings).

In the modification of the adjusting means shown in Figs. 6 and 7, the washer 14 is 15 constructed in the manner described above and provided with inwardly projecting pins 16; but the washer 19 described above is replaced by a washer 19^a shaped exactly the same as the washer 14. Both of the washers 20 14 and 19^a are provided with arms 15^a and 15^b, respectively, extending in the same direction; and said arms are interconnected by means of a bolt 20 and a sleeve-shaped distance piece 21, so that they will be rotated simultaneously during the adjustment 25 in a manner easily understood without further explanation. Besides, the washers 14 and 19^a are also interconnected by means of the central bolt 7^a which serves as a pivot 30 for the rotatable parts, as described above. This modification of the adjusting means may naturally be used only if the washers are to be turned through a comparatively small angle for a complete adjustment of 35 the whole width of the grip, as will easily be understood, and in such case the handle 1 need not take that angular position with respect to the path of relative movement of the jaws as shown in the drawings, but may 40 be positioned substantially parallel to such path of movement, or at a small angle to the same.

According to Figs. 8 and 9 the wrench head 2, at that part facing backwardly towards the handle 1, is provided with a circumferential groove 22 for coaction with a corresponding flange or shoulder 23 (Fig. 9) on the rear side of the arm 15^c on the adjusting member 14 provided with the pins 16, as described above. A tool of the kind in question will often be thrown about in a rather careless manner, and the purpose of the construction just described is to prevent the arm 15^c from being bent, or the rather thin adjusting member from being deformed, if the arm 15^c for instance should be struck a heavy blow from the rear side.

According to Fig. 10 the adjusting member or washer 14 is provided with a plurality of arms 15^d, and the figure shows four of them. This embodiment is to be used when the gearing ratio between the toothed transmission members adapted for displacement of the movable jaw is such that the adjusting member 14 must be turned more than one

half revolution for a complete adjustment between the minimum and maximum gripping widths.

The modifications just described and shown in Figs. 8, 9 and 10 respectively may 70 of course be used in connection with any or all of the embodiments of the wrench described with reference to Figs. 1-5 above.

According to Figs. 11 and 12 the locking disc 10^b connected with the toothed wheel 6 at the circumference is provided with a number of pivotally mounted locking pawls 24, which are spring actuated so as to have a permanent tendency to go into engagement with a toothed ring 25, rigidly mounted 80 within the cavity of the wrench head. The adjusting washer (removed in Fig. 11) is provided with pins 16 which project behind the pawls 24 for disengaging the same when said washer is turned in a counter clockwise 85 direction. One of the pins 16^a acts to form a driving means for the locking disc when the pawls are disengaged, and for such purpose the said pin coacts with a spring 26 mounted in a circumferential recess in the 90 disc. The said spring is guided by a circumferentially extending pin that also forms an abutment for the pin 16^a for limiting the compression of the spring, and an arc-shaped plate 27 protects the turns of the 95 spring from interfering with the teeth on the ring 25 when the locking disc is to be turned.

What I claim and desire to secure by Letters Patent is:—

1. An adjustable wrench comprising a handle member, a wrench head rigidly connected therewith and provided with a transverse cavity one edge of which forms a fixed locking abutment, a fixed jaw rigidly connected with said head, an adjustable jaw mounted in the head for movement in relation to the fixed one, a toothed rack member connected with the adjustable jaw, a disc rotatably mounted within said cavity, means connected with the disc and provided with a peripheral row of teeth positioned in mesh with said toothed rack, the edge of said disc having circumferentially extending recesses facing the fixed abutment surface, locking means provided within said recesses and adapted for coaction with said abutment surface, means for effecting an automatic locking action of said locking means, and means for manually releasing the locking means in counteraction to the means for effecting the automatic locking action.

2. An adjustable wrench according to claim 1 and comprising the additional feature that the releasing means consists of a disc rotatably mounted in the wrench head and provided with means projecting inwardly into the circumferentially extending recesses in the disc member.

3. An adjustable wrench according to claim 1 and comprising the additional features that the peripherally toothed means and the manual releasing means are all rotatably mounted around a common axis of rotation, and that the fixed locking abutment consists of a surface within the wrench head cavity, which surface is concentric with the common axis of rotation.
- 5 4. An adjustable wrench comprising a handle member and a wrench head rigidly connected therewith, a fixed jaw rigidly connected with said head, an adjustable jaw mounted in the head for movement in relation to the fixed one, a toothed rack member connected with the adjustable jaw, a transmission member rotatably mounted in the wrench head and provided with peripherally teeth in mesh with said toothed rack, a locking disc connected with said transmission member and provided at its circumference with a number of peripherally extending recesses, a corresponding abutment surface in the wrench head located in opposition to said recesses and forming together with the wrench head a corresponding number of spaces tapering towards one end, a movable locking means in each of said spaces, spring means for pressing said locking means towards the smaller ends of the spaces, an adjusting member rotatably mounted in the wrench head and provided with inwardly projecting pin members positioned at that side of the movable locking means not acted upon by the springs, and means for manually rotating the adjusting member.
- 10 5. An adjustable wrench comprising a handle member and a wrench head rigidly connected therewith, a fixed jaw rigidly connected with said head, an adjustable jaw mounted in the wrench head for movement in relation to the fixed one, the wrench head having a transverse cavity extending therethrough, a transmission member rotatably mounted within said cavity and provided with a peripheral row of teeth, a toothed rack member connected with the adjustable jaw and meshing with the teeth of the transmission member, a locking disc rigidly connected with said transmission member, a concentric abutment surface within said cavity positioned in opposition to said disc, automatically-acting interlocking means positioned between said disc member and abutment surface, an adjusting washer positioned as a closure the cavity in the wrench head at one side of the latter, means for effecting manual rotation of the said washer, inwardly extending projections on the adjusting washer for releasing the interlocking means, a washer member closing the cavity at the opposite side of the wrench head, and a transverse bolt member interconnecting the said washers and forming a common axis of rotation for the transmission member, the locking disc member and the adjusting washer.
- 15 6. An adjustable wrench according to claim 5 and comprising the additional feature that the closure washer placed in opposition to the adjusting washer is combined with the latter so as to rotate together therewith.
- 20 7. An adjustable wrench comprising a handle member and a wrench head combined therewith, a fixed jaw connected with the wrench head, an adjustable jaw mounted in said head for movement in relation to the fixed one, a toothed rack member connected with the adjustable jaw, a toothed transmission member rotatably mounted in the wrench head in mesh with said toothed rack member, a locking disc connected with the transmission member to rotate together therewith, a fixed abutment surface in the wrench head, automatically-acting locking means interposed between said locking disc and abutment surface, arresting means having a limited power of retardation acting upon said locking disc, and a manually-operable adjusting means for releasing said locking means.
- 25 8. An adjustable wrench comprising a handle member, and a wrench head rigidly connected therewith, a fixed jaw connected with the wrench head, and an adjustable jaw mounted in said head displaceably in relation to said fixed jaw, a toothed rack member connected with the adjustable jaw, a toothed transmission member mounted to rotate around a fixed axis in the wrench head and positioned in mesh with said toothed rack member, a fixed abutment surface in the wrench head rigidly connected with the handle member, a locking disc rotatably mounted around the same fixed axis as the toothed transmission member, locking means interposed between said abutment surface and the locking disc, means for automatically actuating said locking means for the purpose of locking, and means for manual release of said locking means.
- 30 9. An adjustable wrench according to claim 8, and comprising the additional feature that the locking means consists of a friction locking device.
- 35 In testimony whereof I have signed my name to this specification.
- 40 JOHAN PEHRSSON.
